UNITED STATES PATENT OFFICE.

EDWIN C. FABER, OF PHILADELPHIA, PENNSYLVANIA, ASSIGNOR TO PROCTOR & SCHWARTZ, INCORPORATED, OF PHILADELPHIA, PENNSYLVANIA, A CORPORATION OF PENNSYLVANIA.

DRIER.

Application filed May 6, 1922. Serial No. 553,893.

To all whom it may concern:

Be it known that I, EDWIN C. FABER, a citizen of the United States, residing in Philadelphia, Pennsylvania, have invented 5 certain improvements in Driers, of which the following is a specification.

My invention relates to certain improvements in driers, especially those used in drying ceramic ware, but it will be understood 10 that the drier can be used for drying other materials without departing from the essential features of the invention.

One object of the invention is to provide a drier with a rotating table upon which the 15 material to be dried is placed, and a further object of the invention is to provide means for circulating heated air in the drier while the position of the material is being shifted in respect to the currents of heated air.

20 In the accompanying drawings:

Figure 1, is a sectional elevation of a drier made in accordance with my invention;

Fig. 2, is a sectional plan view of the drier shown in Fig. 1;

25 Fig. 3, is a sectional elevation of a drier having side circulating passages;

Fig. 4, is a sectional plan view of Fig. 3;

Fig. 5, is a sectional elevation of a modification of the drier shown in Fig. 1;

30 Fig. 6, is a sectional plan view of Fig. 5;

Fig. 7, is a view of a drier in which the turntable is mounted on a vertical shaft, and illustrating an overhead drive;

Fig. 8, is a sectional plan view of Fig. 7;

35 Fig. 9, is a sectional elevation of a drier in which the material to be dried is mounted on a series of platforms or tables carried by a single vertical shaft;

Fig. 10, is a sectional plan view of Fig. 9;

40 Fig. 11, is a sectional elevation of a drier having a centrally located turntable and a circulating fan at each end, and

Fig. 12, is a plan view of the drier shown in Fig. 11.

45 Referring in the first instance to Figs. 1 and 2, 1 is the casing of the drier. Some distance from one end of the casing is a vertical partition 2 in which is an opening 3. Located in the opening is a circulating fan 4

50 mounted on a horizontal shaft 5 extending through one end of the casing 1 and having a belt pulley 6 thereon for a power driven belt.

7 is a base located within the casing and

having a step bearing for a short vertical 55 shaft 8 on which is mounted a turntable 9 for supporting the ceramic ware or other material to be dried. The drawing illustrates a sagger A. On the shaft 8 is a worm wheel 10, with which meshes a worm 11 on a horizontal shaft 12, on which is a belt pulley 13.

A horizontal partition 17 extending from the lower edge of the vertical partition conforms to one side of the turntable so as to 60 cause the air to circulate over the turntable and return under the table to the space back of the fan, as shown by the arrows. In the space back of the fan in the present instance are heating pipes 14 which may be of any 65 form and arranged in any manner desired. In the present instance, I provide deflectors or shutters 15 in front of the fan. These shutters are preferably pivoted so that they can be adjusted to allow more or less air to 70 circulate and to direct the air as desired.

At the end of the casing opposite to the fan are doors 16 to allow for the loading of the turntable with material to be dried and to remove the dried material.

80 It will be seen that as the heated air is circulated, the material being dried is turned, and if more than one article is being dried, the position of the different articles is changed, so that the article or articles are 85 more evenly dried than when they are mounted on a non-rotating support.

In Figs. 3 and 4, a modification is illustrated, in which the air is circulated in a horizontal path. 1^a is the casing. 2^a is a vertical partition having an opening in which a circulating fan 4^a is located. 17^a is a horizontal partition closing the lower portion of the casing in which the driving mechanism for the turntable 9^a is located. 90 18 are two partitions extending forward from the vertical partition 2^a, one on each side of the turntable 9^a. These partitions preferably extend to the full height of the drier and terminate short of the forward end of the casing to form a circulating passage. The partition 2^a in this instance terminates at the side partitions 18 so as to 95 allow for free circulation of air, as shown in Fig. 4. 14^a are coils of heating pipes, and 15^a are the deflectors or shutters. 100 Doors 16^a are at the front end of the drier.

105 In Figs. 5 and 6, a drier is shown in

which the fan 4^b is mounted on a vertical shaft 5^b extending through the roof of the drier and driven in any suitable manner. A horizontal partition 19 having an opening for the fan is connected to a vertical partition 2^b extending across the drier and having an opening therein, in which are located the shutters 15^b. The heating pipes 14^b are located in the space back of the partition 2^b and under the fan. The turntable 9^b is driven in the same manner as the table shown in Fig. 1.

In Figs. 7 and 8, the turntable 9^c is mounted on a vertical shaft 8^c having its lower bearing in a step 7^c and extending through an upper bearing 20 in the roof of the drier. On this shaft 8^c is a worm wheel 10^c driven by a worm on a shaft 12^c. In this instance two circulating fans 4^c are shown, and there are two vertical partitions 2^c separated by a channel 21 formed by two short longitudinal partitions 22. The heating pipes are located back of the fans and the channel. The circulation of heated air is clearly shown by the arrows in Fig. 8.

In Figs. 9 and 10, I have shown a series of turntables or platforms 9^d on a vertical shaft 8^d driven from above. The shaft 8^d is mounted in bearings similar to the shaft in Fig. 7, and the lower turntable preferably rides on rollers 23 located under the table near the outer edge. In this instance, the air is circulated in a horizontal path as in Fig. 4.

In Figs. 11 and 12, the turntable 9^e is located at the center of the drier casing 1^e, and there is a circulating fan 4^e at each end of the drier, the fans being located between two partitions 22^e. The air circulates in a horizontal path over the center of the turntable, returning over each side of the turntable, as shown by arrows, Fig. 12. There are doors at each side of the casing opposite the turntable.

In each one of the machines described above, the material is rotated as it is subjected to heated air in circulation, thus thoroughly and evenly drying the material.

I claim:

1. The combination in a drier, of a casing enclosing a drying chamber; a turntable located within the chamber, the table supporting the material to be dried; means for circulating air across the table and in

contact with the material; and means for heating the air in circulation.

2. The combination in a drier, of a casing enclosing a drying chamber; an imperforate turn-table located within the chamber, the table supporting the material to be dried; means for circulating air across the table and in contact with the material mounted on said table; and means for heating the air in circulation.

3. The combination in a drier, of a casing enclosing a drying chamber; a turntable located in said chamber; a driving shaft and worm gearing through which the table is turned by the shaft; a fan at one end of the drier for circulating air in the chamber; and means for heating the air.

4. The combination in a drier, of a casing enclosing a drying chamber; a base; a vertical shaft mounted on the base; a turntable carried by the shaft; a driving shaft geared to the vertical shaft; a partition having a fan opening therein; a circulating fan located in said opening; a shaft on which the fan is mounted; and means for heating the air in circulation.

5. The combination in a drier, of a casing enclosing a drying chamber; a vertical partition located near the rear end of the casing and having a fan opening therein; a circulating fan in said opening; heating means in the space between the partition and the back wall of the casing; a turntable located in the space between the partition and the front of the casing; and a door in the front of the casing.

6. The combination in a drier, of a casing enclosing a drying chamber; a vertical partition in said chamber; a turntable on one side of the partition; heating means on the other side thereof; a horizontal partition extending from the lower end of the vertical partition to the turntable; and means for circulating air in said chamber.

7. The combination in a drier, of a casing enclosing a drying chamber; a vertical partition in said chamber; a turntable in the chamber; means for circulating air around the partition and over the turntable; and shutters for controlling the flow of air, said shutters being located between the partition and the turntable.

EDWIN C. FABER.
